ATTORNEY

UNITED STATES PATENT OFFICE

JACQUES KREISLER, OF NEW ROCHELLE, NEW YORK, ASSIGNOR TO JACQUES KREISLER & CO., OF NEW YORK, N. Y.

JEWELRY

Application filed September 7, 1929. Serial No. 390,905.

This invention relates to improvements in terminal snaps for the ends of the fabric or metal cord used in wrist watch bands, and has reference particularly to a snap which may be readily attached to the ends of the cord without any previous preparation thereof, and which has certain novel features making it extremely simple to couple and uncouple.

10 My invention has for its object to provide a terminal snap of this character having small dimensions without detracting from its efficiency and safety as a coupling for wrist watch bands.

15 I accomplish this object by means of the arrangement and combination of parts hereinafter described in the specification, set forth in the claims and illustratively exemplified in the accompanying drawings, in 20 which, Figure 1 is a plan view of a wrist watch band having my improved terminal snap attached thereto; Figure 2 is an enlarged bottom plan view of the snap in coupled position; Figure 3 is a substantially longitudinal 25 view taken on lines 3—3 of Figure 2; Figures 4 and 5 are perspective views of the two sections of the snap in uncoupled position; Figures 6, 7, 8 and 9 are detail perspective 30 views of the blanks from which the several parts of the snap are formed.

Referring to the drawings, 10 denotes a 35 wrist watch band consisting of two lengths of cord 11, which may be of either fabric or metal. Each length of the cord 11 is folded over to form a loop 12 at one end to receive the link 13 adapted to be mounted on a pin or bar at the end of the watch casing. The opposite ends of strip of cord are disposed side by side and at their ends are attached 40 to one member or section of the terminal snap.

One of the sections of the snap forms the eye and is shown in Figure 5 ready to be applied and in blank form in Figure 7. The blank 14 from which the eye is formed 45 comprises a piece of metal having a central portion, side wings 15 which are bent downwardly at right angles to the mid portion to form the sides. The mid portion is shaped into two parallel semi-cylindrical parts 16.

50 The forward ends of each side portion are

tapered and project forwardly to provide guide pieces 17. The mid portion is also provided with a tongue 18 projecting outwardly between and beyond the guide pieces 17, the end of the tongue being provided with a 55 square opening or eye 19. The portion of the tongue between the eye 19 and cylindrical portions 16 is bent downwardly at right angles to form a wall 20 from which the eye portion 19 is bent at right angles to lie parallel with the axis of the snap and abuts the inner faces of the guides 17 at its sides. The corners of the blank forming the sides 15 are provided with openings 21 to accommodate the projections 22 of a clamping plate 23. 60 The plate 23 is provided with upturned teeth 24 on line with the axis of projections 22 so that when the ends of the cord 11 are placed in the grooves 16 and the clamping plate 23 is pressed down into the sides 15, the teeth 65 24 will bite into the surface of the cord and securely hold it in position within the section of the snap. It will be seen that the position of the clamp plate 23 and its teeth 24 are such that outward strain on the cord 11 only tends to swing the plate inwardly against the surface of the cord and the teeth 24 deeper into the surface thereof.

The other hook member of the snap is 70 illustrated particularly in Figure 4 and in blank in Figure 6. The blank 25, from which the hook member is formed, comprises a piece of metal having a central portion and side wings 26, the latter being similar to the sides 15 of the eye member. The mid portion is 75 provided with two parallel semi-cylindrical parts 27 and at its forward end a tongue 28 extends outwardly beyond the ear pieces 29 which are projecting portions of the sides 26. The tongue 28 is bent first downwardly and 80 then forward to be disposed between the two ears 29 and at its end is provided with a slightly tapered projection 30, the end of which is turned upwardly in a curve to form a spring hook 31. The rear corners of the 85 blank are provided with holes 32 to receive projections 22 of a second clamping plate 23. The ear portions 29 are also provided with openings 33 which are alined when the blank 90 is shaped up and in these openings 33 the 100

ends of a pintle pin 34 are mounted. Pivotally mounted on the pin 34 is a snap locking tongue 35. The tongue 35 is illustratively exemplified in Figures 3, 4 and 8 and comprises a strip of metal bent upon itself at one end to form a bearing 36 to embrace the pin 34, the opposite or free end being bent to form a hook 37 adapted to snap over the upturned hook end 31. A small projection 38 is mounted on the upper portion of the hook 37 to enable the wearer to disengage the two hooks from each other.

After the two sections of the terminal snap are attached to the ends of the cords 11, coupling thereof is effected by bringing the sections together so that the hook 31 is engaged under the cross bar at the end of the eye 19. The other hook or tongue 35 is then brought down and sprung over the hook 31. This arrangement provides a secure coupling as well as a flexible joint for a wrist band and because of the extreme simplicity of the parts, the entire terminal snap is of a relatively small size, a point which is highly desirable in devices of this character.

Having now described my invention, what I claim and desire to secure by Letters Patent is:

A terminal snap for a wrist watch band comprising separate sections of cord to be separably coupled together, and comprising two sections, each section thereof being provided with a longitudinally fluted upper wall to partly embrace an end of each cord, a clamping jaw mounted in each section for engaging the sections to the cords, the sides of the sections being projected forwardly to provide parallel ears, one section having a projecting tongue disposed between its ears and provided with an eye in the end thereof, the other section having a tongue disposed between its ears and turned upwardly at the end to form a hook to engage the eye from underneath, a pintle pin supported between the ears of the second section, and a pivoted tongue mounted on the pin in the second section and provided with a downwardly turned hook end to spring over the first hook to hold the eye loosely between the two tongues.

In testimony whereof he has affixed his signature.

JACQUES KREISLER.
